UNDERSEAL CUTTER

Leland L. Harder, Hibbing, Minn.

Application September 12, 1951, Serial No. 246,292

2 Claims. (Cl. 30—299)

1

This invention relates to tools and has special reference to a device for clearing so-called "underseal" from bolt heads and the like.

My invention has particular utility in the repair of automobile bodies, and the like. In northern parts of the country, particularly, it is often necessary to use certain chemicals on roads and streets to melt ice accumulations and these chemicals usually have an adverse "eating action" on the metal parts of the auto body, particularly the under side thereof. It has become common practice to coat the under-surface of an auto body with a heavy layer of a somewhat plastic compound called "underseal." This underseal coating materially reduces the possibility of the vehicle body and frame becoming rusted or otherwise "eaten away" by chemicals or weathering action during the life of the vehicle.

Of course, all bolt heads and nuts are also coated with the underseal and when it is necessary to service the vehicle, such as for body repairs, the bolts and nuts are particularly difficult to remove as it is difficult to seat a wrench adequately to permit loosening the nut or bolt. Mechanics usually heat a screwdriver, or similar tool, try to scrape the underseal away from the nuts or bolts to be removed. This is a very costly and time-consuming proceeding which is annoying to the mechanic, to say the least.

It is, therefore, one of my principal objects to provide a means for removing underseal, or the like, from nuts and bolts to permit the firm engagement of a wrench, or similar tool, thereon for removal thereof in a most convenient manner.

Another object is to provide such a device which is simple in structure, yet efficient in operation.

Another object is to provide a tool head which may form a part of a set of so-called socket wrenches whereby the socket wrench operating handle may be used to operate the underseal cutter or remover, and storage of the tool head will not be a problem, as it may be kept with a mechanic's socket wrench set.

Another, more specific, object is to provide an underseal cutter which creates a circular channel around the head of the bolt or nut to be removed and also cleans the underseal from the flat, angularly disposed faces of the nuts and/or bolts to permit adequate seating of a wrench, such as a socket wrench, on the nut or bolt head.

These and other objects and advantages of my invention will become more apparent as the description proceeds.

2

In the accompanying drawing forming a part of this application:

Figure 1 is a perspective view of one of my underseal removers or cutters.

Figure 2 is a side elevational view of the device shown in Figure 1 illustrating the position of my device after completing a cutting operation around a bolt head.

Figure 3 is a sectional view on the line 3—3, Figure 2.

Figure 4 is a rear edge view of one of the cutter blades.

Figure 5 is an elevational view of Figure 4.

Figure 6 is an enlarged sectional view on the line 6—6, Figure 5.

In the drawing, the reference numeral 1 indicates the body member of my underseal cutter, which may comprise a cylindrical block of metal as shown, or some other form suitable for the purpose.

The body member 1 could be provided with a suitable handle, not shown; however, I prefer to provide an opening or socket 2 substantially axially of the body member, the socket being of suitable size and of rectangular shape, as shown, whereby a conventional socket drive handle may be operatively connected to the body member by inserting the rectangular drive member in the socket 2 so that my cutter can be operated in the manner of conventional socket wrenches.

I have provided a plurality of blades 3 which are secured to the body member in any desired manner to be rotated with the body member by the operating or drive handle. The blades preferably extend from the body member with their axes in substantially parallel relation to each other and to the axis of rotation of the body and are spaced substantially equi-distant apart on the periphery of the body member, as shown. I have found that three blades are adequate for most practical working conditions.

The blades 3 are elongated and of equal length, as shown, and are made of spring steel. The blades are provided adjacent their outer ends with cutters which comprise a bottom edge 5 which is upwardly inclined from the forward or leading edge 6 toward its rear or trailing edge 7. As shown in the drawings, the blades are somewhat of V-shape, having a bend 8 transversely thereof in slightly spaced relation to the bottom edge 5, the bend being in a plane substantially normal to the axis of rotation of the cutter device. The said V-shape permits the blades to center themselves on the nut or bolt head Q

quickly and accurately, and, in addition, the blades are free to straddle the nut or bolt head and grip same firmly because the blades are of spring steel and are so constructed and arranged that they must be sprung outwardly in order to straddle the nut.

This feature insures that the wrench engaging corners 9 and faces 10 are cleaned substantially entirely of underseal 11, as will become apparent.

In operation, with a suitable handle in place on the body member, the blades 3-3 are placed against the nut or bolt head and pressure is applied thereto against the nut or bolt head while the body member is rotated. It takes very little skill or "practice" to gauge what pressure is most desirable against the blades to force them to spread and encircle the nut or bolt head and to force them through the underseal 11 at the desired speed to do the most desirable cleaning of the nut or bolt head. The blades rotate in jerks, so to speak, as it takes more effort to rotate the blades from a point where they engage the flat faces 10 of the nut or bolt head around the corners 9 thereof, as the blades must be spread apart against their spring tension in order to round the corners; however, each portion of the nut or bolt head is engaged and cleaned by the blades.

The blades 3 are preferably mounted or provided with a slight twist, as shown at 12, whereby the trailing edge 7 of the cutters do not run in the same peripheral plane as the leading edge 6, but are flared outwardly to run in a separate, wider plane whereby a relatively wide channel is provided in the underseal around the bolt head or nut, as shown in Figure 2, making it a simple matter to engage a common socket wrench over the nut or bolt head to remove same.

It is to be understood that I have herein shown and described one specific embodiment of my invention, and that my appended claims are not necessarily limited specifically thereto, but should be construed as broadly as permissible in view of the prior art.

Having thus described my invention, what I claim is:

1. A device for removing substances such as underseal from around nuts and the like comprising: a cylindrical body member, a socket in one end of said body member and substantially axially aligned with same to receive a handle for rotating said body member, at least three elongated blades fixed to said body member in substantially equally spaced relation to each other around the periphery of said body member, said blades extending from said body member with their axes in substantially parallel relation to each other and to the axis of rotation of said body member, and cutters on the outer ends of said blades for engagement around said nuts to remove said underseal from around said nuts as said body member and blades are rotated axially, said blades being of spring metal and being adapted to be forced apart to firmly engage said nuts at all times while being rotated therearound to clean said nuts of underseal as said cutters enter said underseal, said cutters comprising a bottom edge which is upwardly inclined from the leading to the trailing edge thereof to permit said leading edge to enter and lead into said underseal, and said trailing edge being flared outwardly farther than said leading edge of the cutter so as to travel in a greater peripheral path than said leading edge whereby a relatively wide channel is cleared around said nuts to receive a nut removing tool.

2. The structure as set forth in claim 1 and said cutters having a transversely disposed V-shaped bend therein with the apex of said V-shape inwardly disposed to engage said nuts and to permit the ready application of said blades over and around said nuts.

LELAND L. HARDER.
